UNITED STATES PATENT OFFICE.

OSCAR FAIRLESS, OF BLACKFOOT, IDAHO.

AUTOMOBILE SAFETY SIGNAL.

Application filed October 4, 1926. Serial No. 139,538.

The present invention relates to a signal for automobiles and has for its object to provide a simple and efficient structure which embodies a casing with a pair of arms 5 swingably mounted therein and means for operating said arms.

In the drawing:

Figure 1 is a front elevation of the device embodying the features of my invention,

10 Figure 2 is a vertical section therethrough,

Figure 3 is another vertical section taken at right angles to that shown in Figure 2 and substantially on the line 3-3 of Figure 1.

15 Referring to the drawing in detail, it will be seen that the numeral 1 denotes a casing having its sides open, a pair of signal arms 2 are pivoted in the top of the casing as at 3. A spring 4 is connected to the arms 2 so as to normally maintain the arms in the casing, that is in a non-signalling position. Cables 5 are attached to the arms as at 6 and cross each other as at 7, then pass over a socket 8 extending through the casing and 20 then cross each other a second time as at 9 and pass through space openings 10 in the bottom portion of the casing to be operated in any desired manner at a remote point. A second socket 11 extends through the

lower portion of the casing. Lamp housings 12 and 13 are carried by the sockets 8 and 11 respectively.

It is thought that the construction, operation, and advantages of this invention will now be quite apparent to those skilled in this art. It is apparent that changes in the details of construction, and in the combination and arrangement of parts may be resorted to without departing from the spirit or scope of the invention, as hereinafter 40 claimed or sacrificing any of its advantages.

Having thus described my invention, what I claim as new is:

A signal of the class described comprising a casing, a pair of arms pivoted in the upper portion of the casing, spring means connected with the arms to normally hold said arms inwardly of the casing, cables connected to said arms for swinging said arms outwardly of the casing to signalling positions, said cables crossing each other, a member projecting through the casing and over which said cables pass, said cables crossing each other a second time, and being extended through openings in the bottom portion 50 of the casing.

OSCAR FAIRLESS.
